JOSEPH BIJUR, OF NEW YORK, N. Y., ASSIGNOR TO THE SAFETY CAR HEATING AND LIGHTING CO., OF NEW YORK, N. Y., A CORPORATION OF NEW JERSEY.

ELECTRICAL SYSTEM.

1,317,476.

Specification of Letters Patent. Patented Sept. 30, 1919.

Application filed March 9, 1911. Serial No. 613,425.

To all whom it may concern:

Be it known that I, JOSEPH BIJUR, a citizen of the United States, residing at New York, in the county of New York and State 5 of New York, have invented certain new and useful Improvements in Electrical Systems, of which the following is a full, clear, and exact description, such as will enable others skilled in the art to which it appertains to make and use the same.

This invention relates to electrical regulating systems. One of the objects thereof is to provide simple and practical apparatus for regulating voltage. Another object is 15 to provide apparatus of the above nature in which the action is sensitive and the regulation accurate. Another object is to provide means in connection with apparatus of the above general nature for enhancing its 20 economy in action. Other objects will be in part obvious and in part pointed out hereinafter.

The invention accordingly consists in the features of construction, combinations of 25 elements and arrangement of parts which will be exemplified in the construction hereinafter set forth, and the scope of the application of which will be indicated in the following claims.

30 In the accompanying drawing, wherein is shown one of various possible embodiments of this invention,—

Figure 1 is a diagrammatic plan of the same.

35 Fig. 2 is a plan of a regulating device.

Fig. 3 is a side elevation of the device shown in Fig. 2.

Similar reference characters refer to similar parts throughout the several views of the 40 drawing.

Referring to this drawing now in detail, there is shown in Fig. 1 a generator 1 provided with a shunt field 2 and having any desired form of regulating apparatus for 45 the generator output. Between the generator mains 3 and 4 are bridged a storage-battery 5 and lamps or other translating devices 6. The circuit through the main 4 is interrupted at the contacts 7, connection be- 50 tween which is controlled by a switch member 8 which is retracted by an adjustable spring 9. The raising of member 8 and completion of the circuit through the main 4 is controlled by a voltage coil 10, bridged 55 about the generator terminals, this coil act-

ing cumulatively with a series coil 11 traversed by the charging current from the generator.

Serially connected in the main 4, between battery 5 and lamps 6, is a variable resistance medium, diagrammatically indicated at 12. The device comprising this medium is shown in detail in Figs. 2 and 3 of the drawing, and it may be noted by reference to these figures, that it includes a number of sets of carbon disks, these sets being indicated at 13 and being here shown as six in number. Any desired means may be employed for holding the disks in alinement and leading current through them in parallel. Upon each group of three sets of disks is mounted a pressure plate 14 and these plates have a ball-joint connection at 15 with a cross-arm 16 which in turn has a ball-joint connection with a set-screw 17 and a pivoted lever 18. The latter member is jointed to a support 19 upon the base 20 and extends beyond its pivot at 21 to a set-screw 22, between which and the base 20 are positioned a short spring 23 and a somewhat longer spring 24. These springs are connected one with another and at their point of connection have secured thereto a collar 25, which rests upon an arm 26 through which the spring freely passes. This 25 collar serves to maintain the spring 24 in a state of tension, even when the extension 21 of lever 18 is depressed, but the short spring 23 acts freely and with the above position of the lever 18 is in a normal or undistorted 30 state.

Coacting with the free end of lever 18, which is provided with an armature 27, is a magnet 28 having a fixed core 29. The winding of this magnet will be hereinafter 35 described in detail, but it may here be noted that as it draws the armature 27 toward the core 29 its pull upon the latter, even with a constant field strength, rapidly increases, due to the decreasing distance between these 40 parts. The various parts are so formed and proportioned that the rate of increase of pull upon the armature with a substantially constant field strength of the magnet is equal to the rate of increase of mechanical resist- 45 ance to compression of all of the carbon disks after they have been brought firmly into contact. There is a range of compression 50 of these disks, however, which it is desired to utilize in the action of the apparatus, in 55

which **they** offer substantially no resistance to a compressing movement, as they are not firmly in contact one with another. It will be seen that unless means were provided for 5 affording a rapidly increasing resistance to movement of the armature throughout this last mentioned range, it would upon moving from its position of extreme retraction immediately pass over this range of extremely 10 light contact, as any approaching movement would of itself cause a rapid increase in attractive force which would be unbalanced until the disks were firmly in contact. Accordingly the spring 23 is provided in 15 undistorted form with the armature fully retracted and this spring is so proportioned as to provide a rapidly increasing retractive force, and thus cause the compression of the disks, even in their range of lightest contact, to be substantially proportional to the 20 field of magnet 28. Throughout this range of action of the spring 23 it acts quite independently of spring 24, and hence a given linear movement of lever end 21 will result 25 in a much greater proportional increase in its length than if both springs were acting together and will increase its retractile force at a proportionally rapid rate. When, however, its tension is equal to that of the 30 spring portion 24, both springs act as a single spring and any given increase of length forms a much smaller proportion of the total spring acting. The parts are so formed that spring 24 is brought into action 35 substantially as the disks come into firm contact and of themselves offer a rapidly increasing mechanical resistance to compression. Thus, springs 23 and 24 act conjointly in giving first a rapidly increasing and then 40 a uniform and substantially unincreasing retractile force of a value which is equal to the difference in the attractive force of the magnet and the mechanical resistance of the carbons. In other words, the forces 45 tending to oppose downward movement of the armature 27 are the rapidly increasing retractile effect of spring 23, followed by the substantially constant retractile effect of this spring, together with spring 24, and 50 the mechanical resistance to compression of the carbons, which is substantially zero until they are firmly in contact, but rapidly increases from this point up to the point of maximum compression. The resultant of 55 these forces is a rapidly increasing resistance to any movement of the armature toward the core, and the magnet core and armature are so formed and proportioned that with a constant field strength the pull upon the 60 armature as it approaches the core increases at a slightly less rapid rate than this resultant of the opposing forces. It accordingly follows that the position of the armature varies with the field strength of the magnet 65 and that the resistance of the medium 12

will have a value which is proportional to this field strength.

As shown in Figs. 2 and 3 of the drawing, there is provided a shield 30 which curves about the magnet 18 and guards it from the 70 heat of the resistance elements which are grouped about the same. It may also be noted that the several ball-joints insure an even pressure upon all of the resistance piles and this pressure may readily be adjusted 75 with the armature in fixed position by means of the set screws 17.

Recurring to Fig. 1 of the drawing, there is shown a voltage magnet 31 bridged across the mains adjacent the lamps 6 and acting as 80 it attracts the lever 32 to relieve pressure upon a pile of carbon disks 33 and thus increase the resistance of the latter. Resistance 33 is positioned in a conductor 34 which is shunted about a differential coil 85 35 on the magnet 28, this coil and resistance element being bridged in series with the main magnet coil 36 across the mains. The coil 36 is of predominating effect in forming the field of the magnet 28, and it will be 90 seen that as the field of coil 31 increases above normal strength the resistance 33 will be increased, which will not only tend to cut down the current flowing through coil 36, but will relatively strengthen the differential coil 35 and produce a marked weakening effect upon the resultant field of the magnet 28. Conversely, an abnormally 95 weak field of the coil 31 will produce an abnormally strong field of magnet 28. 100

Inasmuch as it is desired to avoid potential drop in the resistance medium 12, when the voltage across the mains is not unduly high, there are provided a series of plates 37 electrically connected one with another 105 and respectively positioned in each of the several resistance piles 13 and also electrically connected with a contact 38. The adjacent contact 39 is connected by conductor 40 with the main 4 and contacts 38 and 39 are connected one with another by the switch element 8 when it is in retracted position, as shown in Fig. 1 of the drawing. With the main switch in this position the generator 110 is disconnected from the battery and nothing higher than battery voltage is imposed upon the mains, and the above connections shunt out a large portion of the resistance medium 12 and correspondingly enhance the economy of the system. 115

In order that the meaning of certain terms used in the following claims may be clear, it may be noted that the term "lamp" is intended to include any form of translating devices, and the expression "distorted," as with reference to the spring, is intended to indicate any deformation from a free, natural position. 120

In the operation of the above system, the contacts 7 are connected when the generator 130

has attained a sufficient voltage to charge the battery, by reason of the action of coil 10, and any tendency of the battery to discharge back through the generator will cause coil 11 to act differentially and open the circuit. When the contacts 7 are connected, the voltage across the mains may attain a much higher value than could be the case from the battery alone, and accordingly the entire resistance medium 12 is employed to govern the voltage on the lamps. When, however, the main switch opens, a large portion of this resistance is shunted and the remainder will efficiently control any fluctuations in battery voltage. As above noted, any abnormality in the field of voltage coil 31, which would follow from any tendency to abnormality in the voltage across the lamps, will correspondingly affect the resultant field of magnet 28 and either increase or decrease the value of resistance 12 to precisely the desired amount required to remedy this tendency and hold the voltage normal. The regulating action, for the reasons above pointed out, is accurate and sensitive and the entire range of the resistance medium is efficiently employed.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

1. In apparatus of the class described, in combination, a generator, a storage battery and lamps adapted to receive current from said generator, a device adapted to connect said generator with said battery upon the generator voltage attaining a predetermined value and to disconnect the same upon said battery discharging back through said generator, a pressure-controlled variable resistance medium interposed between said battery and lamps, a shunt coil and a differential coil in series therewith controlling said resistance medium, a variable resistance in shunt with said differential coil and controlled by electro-magnetic means responsive to lamp voltage to vary the effect of said shunt and said differential coils, and means controlled in accordance with the position of said first device adapted to short-circuit

a portion of said medium when said generator is disconnected from said battery and lamps.

2. In apparatus of the class described, in combination, a generator, a storage battery 70 and lamps adapted to receive current from said generator, a device adapted to connect said generator with said battery upon the generator voltage attaining a predetermined value and to disconnect the same upon said battery discharging back through said generator, a pressure-controlled variable resistance medium interposed between said battery and lamps, a shunt coil and a differential coil controlling said resistance medium, a variable resistance controlled by electro-magnetic means responsive to lamp voltage to vary the effect of said coils, and means controlled in accordance with the position of said first device adapted to short-circuit a portion of said medium when said generator is disconnected from said battery and lamps.

3. In apparatus of the class described, in combination, a generator, a storage battery 90 and lamps adapted to receive current from said generator, a device adapted to connect said generator with said battery upon the generator voltage attaining a predetermined value and to disconnect the same upon said battery discharging back through said generator, and a pressure-controlled variable resistance medium interposed between said battery and lamps, an armature connected therewith, a coil having a fixed core in operative relation to said armature to control said resistance medium, the armature approaching the core to increase the pressure of said medium, the parts being proportioned so that the increasing magnetic efficiency of the coil as the armature approaches the core is substantially balanced by the increased opposition of the parts to such movement, and vice versa.

4. In apparatus of the class described, in combination, a generator, a storage battery and lamps adapted to receive current from said generator, a device adapted to connect said generator with said battery upon the generator voltage attaining a predetermined 110 value and to disconnect the same upon said battery discharging back through said generator, a pressure-controlled variable resistance medium interposed between said battery and lamps, an armature connected 115 therewith, a coil having a fixed core in operative relation to said armature to control said resistance medium, the armature approaching the core to increase the pressure of said medium, the parts being proportioned so that the increasing magnetic efficiency of the coil as the armature approaches the core is substantially balanced by the increased opposition of the parts to such movement, and vice versa, and means controlled 120

in accordance with the position of said first device adapted to short-circuit a portion of said medium when said generator is disconnected from said battery and lamps.

- 5 5. In apparatus of the class described, in combination, a generator, a storage battery and lamps adapted to receive current from said generator, a device adapted to connect said generator with said battery upon the generator voltage attaining a predetermined value and to disconnect the same upon said battery discharging back through said generator, a pressure-controlled variable resistance medium interposed between said battery and lamps, a shunt coil and a differential coil controlling said resistance medium, means responsive to lamp voltage for varying the effect of said coils, and means adapted to short-circuit a portion of said medium when said generator is disconnected from said battery and lamps.
- 10 6. In apparatus of the class described, in combination, a generator, a work circuit

adapted to receive current from said generator, a device adapted to connect said generator with said circuit upon the generator voltage attaining a predetermined value, and a pressure-controlled variable resistance medium, an armature connected therewith, a coil energized by the generator and having a fixed core in operative relation to said armature to control said resistance medium, the armature approaching the core to increase the pressure of said medium, the parts being proportioned so that the increasing magnetic efficiency of the coil as the armature approaches the core is substantially balanced by the increased opposition of the parts to such movement, and vice versa.

25 30 35 In testimony whereof I affix my signature, 40 in the presence of two witnesses.

JOSEPH BIJUR.
